HANDLE OR SIMILAR ARTICLE

Harold Jay Greenberg, 1335 Auerbach Ave.,
Hewlett Harbor, N.Y.

Filed Aug. 24, 1965, Ser. No. 86,689

Term of patent 14 years

(Cl. D10—8)

FIG. 1

FIG. 2

FIG. 3

FIG. 4

FIG. 5

FIG. 6

FIG. 1 is a side elevational view of a handle or similar article showing my design, with a support for the handle shown in phantom;

FIG. 2 is a front elevational view thereof;

FIG. 3 is a rear elevational view thereof;

FIG. 4 is a sectional view taken along the line 4—4 of FIG. 3;

FIG. 5 is a sectional view taken along the line 5—5 of FIG. 1; and

FIG. 6 is a side elevational view of an alternative embodiment of my design of a handle or similar article which is identical with the embodiment of FIGS. 1 to 5 except for the elongation of the rear thereof into a substantially truncated conical configuration.

The broken lines are for illustrative purposes only.

I claim:

The ornamental design for a handle or similar article, as shown and described.
